(57) **CLAIM**

The ornamental design for a fluid transfer spout, as shown and described.

DESCRIPTION

FIG. 1 is a top, rear perspective view of a fluid transfer spout showing my new design;

FIG. 2 is a bottom perspective view thereof;

FIG. 3 is a bottom plan view thereto;

FIG. 4 is a top plan view thereof;

FIG. 5 is a rear elevation view thereof;

FIG. 6 is a front elevation view thereof;

FIG. 7 is a left elevation view thereof; and,

FIG. 8 is a right elevation view thereof.

The broken lines in the drawings depict parts of the fluid transfer spout that form no part of the claim.

1 Claim, 7 Drawing Sheets
